UNITED STATES PATENT OFFICE

ABRAHAM WILLIAM ROY, OF LOWELL, MASSACHUSETTS

BRACE MOUNTING

Application filed February 7, 1930. Serial No. 426,661.

This invention relates to certain new and useful improvements in umbrella frame construction and which embodies among other characteristics means whereby the braces and ribs of the umbrella may be separately and independently removed and replaced.

Another object of the invention contemplates the provision and arrangement of bearing structures upon the standards of the umbrella to accommodate appropriate portions of the braces and ribs.

An additional object of the invention consists of holding elements for the bearing structures whereby the journal ends of the braces and ribs will be maintained in position for use.

More specifically stated the bearing structures are slotted to facilitate projecting of the braces and ribs when same are shifted to occupy their respective positions.

With the above and other objects in view, the invention further consists of the following novel features and details of construction, to be hereinafter more fully described, illustrated in the accompanying drawings and pointed out in the appended claim.

In the drawings:—

Figure 1 is a fragmentary elevation of the present form of umbrella frame construction.

Figure 2 is a longitudinal sectional view taken through the bearing structures showing the ribs and braces retracted.

Figure 3 is a sectional view taken through the uppermost bearing construction when separated.

Figure 4 is a view similar to Figure 2 showing the lower slidably mounted bearing construction separated.

Figure 5 is a horizontal sectional view taken on line 5—5 of Figure 2.

Figure 6 is a horizontal sectional view taken on line 6—6 of Figure 1.

Figure 7 is a bottom plan view of the

upper section of the fixed bearing construction.

Figure 8 is a top plan view of the companion portion of the fixed bearing construction.

Figure 9 is a longitudinal sectional view taken through a portion of the slidably mounted separably connected bearing construction.

Referring to the drawings in detail where in like characters of reference denote corresponding parts, the reference character 10 indicates an umbrella staff or standard having spring detent holding elements 11 and 12 arranged in oppositely disposed relation and at spaced intervals in the length of said standard.

The bearing structure for the innermost ends of the ribs 13 of the umbrella comprises a stationary sleeve and a movable sleeve 14 and 15 respectively. The sleeve 14 being held against movement by a cross pin 16 passed perpendicularly through the standard 10 in the manner shown in Figures 1, 2 and 3 of the drawings. The sleeve 15 is provided with slots 17 located upon diametrically opposite sides thereof and longitudinally disposed with relation to the sleeve proper and which are designed to accommodate the projecting extremities of a cross pin 18 when the sleeve 15 is rotated a quarter turn in either direction and when so rotated the sleeve 15 will occupy the Figure 3 position.

The sleeve 15 carries an annular flange 19 outwardly projecting from the upper periphery thereof and which is provided with radially disposed slots 20 therein for the accommodation of the ribs 13, tongues 21 being formed between the radial slots, the purposes and advantages of which will be presently apparent.

The stationary sleeve 14 normally disposed in the positions shown in Figures 1 and 2 of the drawings, that is, the imme-

diate peripheries of the two sleeves, are brought into abutting engagement. The sleeve 14, after the manner of the movable sleeve 15, as provided with a flange 22 of annular contour projecting from the outer surface thereof and spaced from the innermost periphery to facilitate accommodation of the bearing or journal ends 23 of the ribs 13 between the adjacent surfaces of the flanges 19 and 22 respectively. The flange 22, unlike the flange 19 is outwardly and downwardly curved to dispose the marginal edge thereof upon the upper surface of the flange 19 when the journal ends 23 of the ribs 13 are to be locked in position therewith. The curvature of the flange 22 will form a partial housing for the journal ends of the ribs and prevent distortion thereof when said ribs are extended and retracted from their respective positions. Inasmuch as the ribs 13 are to be extended in the manner suggested in Figure 1 of the drawings, it is also necessary to construct the flange 22 in such manner that the radial slots 24 therein will be aligned with the slots 20 in the flange 19. In this manner the ribs 13 may be extended and retracted from the positions shown and the only friction or resistance thereagainst would be the surfaces of the sleeve 14 and the flanges 19 and 22 respectively against which the ball or journal ends 23 of the ribs 13 rock.

The especial form of journal ends or bearing mountings for the ribs 13 is such that tearing of the covering carried by the ribs 13 will be prevented due to misplacement of same thereon as the bearings will permit lateral shifting movement of the rib and prevent such damage. As mentioned in the foregoing, it is necessary that the slots in the flanges 19 and 22 should be aligned to facilitate accommodation of the immediate portions of the ribs 13 to permit same to occupy the Figure 1 and Figure 2 positions and in accomplishing this end I provide a projection 25 upon the upper surface of one of the ears 21 of the flange 19 designed for accommodation within a notch or groove 26 in the edge of one of the ears 27 upon the flange 22 as defined between the radially disposed slots 24.

In umbrella construction, it is also necessary to employ some form of supplemental structure to facilitate supporting of the ribs and these are generally in the nature of braces, such as indicated at 28, pivotally connected, as at 29, in the conventional manner to the inner sides of the ribs 13 at points spaced from the ends thereof. The manner of connecting the innermost ends of the braces 28 with the standard 10 is similar to that as heretofore mentioned in regard to the ribs 13, but in addition there- 65 to the entire mounting is designed for slid-

ing action upon the standard for appreciable distances thereon.

This traveling bearing construction primarily resides in the provision and arrangement of a sleeve member 29' having the flange construction 30 disposed adjacent the middle thereof and which corresponds in every respect to that of the flange 22 save for the particular disposition thereof, that is the flange 30 is oppositely disposed. The sleeve 29' is provided with an elongated slot 31 longitudinally disposed thereon beneath the flange 30 to accommodate the holding element 12 in the manner shown in Figure 2 of the drawings.

A sleeve member 32 telescopically associated with the uppermost portion of the sleeve 29' above the flange 30 therefor, is provided with a flange portion 33 designed for cooperative use with the flange 30 in the formulating of a bearing support for the ball heads 34 formed upon the innermost projecting ends of the braces 28.

The uppermost portion of the sleeve 29' is provided with ears 35 outwardly projecting upon the periphery thereof in diametrically opposed relation. Said ears are designed for selective accommodation within longitudinally disposed slots 36 in the upper peripheral edge of the sleeve 32 when it is desired to separate the flanges 30 and 33 respectively to facilitate removal and replacement of the innermost journaled ends of the braces 28. When the ball heads 34 of the braces 28 are retained against accidental displacement between the aforementioned flanges, the ears 35 override the upper peripheral edge of the sleeve 32 in the manner shown in Figures 1 and 2 of the drawings. The ears of the flanges 30 and 33 respectively are connected together in the manner suggested for the flanges 19 and 22 to align the radial slots therebetween whereby the braces 28 may be extended and retracted with the ribs 13 and to support the latter in the manner shown in Figure 1 of the drawings.

It is obviously apparent that the remaining holding element, namely 11, is to be brought into engagement with the lowermost peripheral edge of the sleeve 29' when the latter is shifted to occupy the Figure 1 position.

The invention is susceptible of various changes in its form, proportions and minor details of construction, and the right is herein reserved to make such changes as properly fall within the scope of the appended claim.

Having described the invention, what is claimed is:—

An umbrella brace mounting comprising a sleeve slidably mounted upon the umbrella staff, a sleeve member telescopically associated for sliding motion upon the sleeve, the sleeve member having slots arranged upon

diametrically opposed sides and adjacent
the outer end thereof, ears carried by and
outwardly projecting from the adjacent end
of the sleeve for selective reception within
5 said slots and for frictional engagement
with the mentioned end of the sleeve mem-
ber, and flanges carried by and oppositely
disposed upon the sleeve and sleeve member
10 to provide a journal housing therebetween
for the ends of said braces.

In testimony whereof I affix my signature.
ABRAHAM WILLIAM ROY.
